UNITED STATES PATENT OFFICE.

EDMUND MOCKEL, OF DUSSELDORF, GERMANY.

DEVICE FOR INSURING CORRECT FINGER POSITION IN WRITING.

Application filed March 29, 1928, Serial No. 265,655, and in Germany March 1, 1928.

This invention relates to a device for insuring correct finger-position in writing. The devices commonly used for this purpose are directly connected with the writing implement, i. e. penholder or pencil, so that the writing implement is no longer freely held between the fingers but is positively guided and consequently exerts on the person who is writing restrictions beyond the purpose of the implement. The pressure of the finger tips upon the writing implement is then no longer fully exerted and the writing no longer fully shows the orthographic individuality of the writer.

In contrast with many guides heretofore constructed the device according to the present invention is not directly connected with the writing implement, which is held freely between the fingers or fingertips. Only the position of the fingers is positively determined. The fingers possess a certain relative movability, and they may slightly alter their relative positions at any moment during the writing. The device may further be used for fingers of almost any thickness, as it is merely necessary to alter accordingly the curvature of the thumb hook and of that of the middle finger, so that this device can be manufactured in large quantities in standard size.

These advantages are obtained by the following structure. The device consists of a sleeve adjustable as regards width, designed to be pushed over the index finger and serving as carrier for an S-shaped clamp which is somewhat curved in the longitudinal direction. One hook-shaped end of the clamp is designed to be placed from above over the middle finger the other hook-shaped end of the clamp serves as support for the thumb, the writing implement resting freely between the tips of the thumb and first two

fingers and upon that portion of the palm of the hand between the thumb and index-finger.

An embodiment of the invention is illustrated, by way of example, in the accompanying drawing, in which:

Fig. 1 shows the device in top plan view.

Fig. 2 shows an end elevation of the same.

Fig. 3 shows the device in a perspective view in the position for writing.

A sleeve *a* of adjustable width serves as holder or carrier for an S-shaped clamp somewhat curved in longitudinal direction and having the hook-shaped ends *c* and *b*. This sleeve *a* is pushed over the index *d* so that the end hook *b* grips from above over the middle finger *e* the hook *c* serving as support for the thumb *f*.

The writing implement *g* rests then freely between the tips of the index and thumb and on the hand, and is completely exposed to the pressure of the finger tips. The implement rests above the portion *h* of the clamp which connects the index-and thumb.

I claim:

A device for insuring a correct finger position in writing, comprising in combination a sleeve adjustable in width designed to be pushed over the index, and an S-shaped clamp slightly curved in the general plane of the material in the longitudinal direction fixed to the lower side of said sleeve the one end hook of said clamp designed to be placed from above over the middle finger and the other end hook supporting the thumb so that the writing implement rests freely between the thumb and index and on the hand, and on the portion of the clamp which connects the index and the thumb.

In testimony whereof I affix my signature.

EDMUND MOCKEL.
